J. W. DE FORD

SYSTEM AND MEANS FOR MARKING STREETS

Filed April 12, 1927

BY

INVENTOR.
John W. De Ford
grossheely

ATTORNEY.

UNITED STATES PATENT OFFICE.

JOHN W. DE FORD, OF LOS ANGELES, CALIFORNIA.

SYSTEM AND MEANS FOR MARKING STREETS.

Application filed April 12, 1927. Serial No. 183,218.

My invention relates to street markers or signs, and the like and pertains more particularly to means and systems for readily enabling pedestrians and motorists to learn

5 the name of the street on which they are approaching or on which they are travelling.

The invention has for its principal object the provision of street marking means, which is so designed as to be thoroughly illuminated 10 by the lights at hand; and in which means the features which render them readily illuminable also render them readable at a considerable and convenient distance.

Another object of the invention is to provide an inexpensive and substantially street marker, which may be readily applied or attached to any light post or the like, and which may be readily incorporated integrally with such posts.

20 Other objects of my invention include economy of installation, economy of operation and illumination, and accruing advantages both to the pedestrians and motorists as well as to the municipality or other body 25 which is responsible for installing same.

Other objects and advantages of my invention will appear hereinafter.

I have illustrated my invention by the accompanying drawings, in which:

30 Figure 1 is a view in elevation of one practical embodiment of my invention.

Figure 2 is a plan view thereof.

Figure 3 is a vertical cross section thereof.

Figure 4 is a view in elevation of a light-35 post to which the said embodiment is applied.

Figure 5 is a diagrammatic plan view of a street intersection showing one practical disposition of light posts of the type shown in 40 Fig. 4.

Figure 6 is a plan view of another embodiment of my invention for special uses.

Figure 7 is a diagrammatic plan view of a street intersection at which the device shown 45 in Fig. 6 is installed.

Figure 8 is a view in elevation of another lamp post showing my invention applied thereto in still another embodiment.

Figure 9 is a fragmentary view in elevation 50 of a modified form of the part shown in Fig. 4.

Referring particularly to Figs. 1 to 5, inclusive, I provide the sign 1 in the form of a rectangular blank of metal bent along its 55 longitudinal median line as at 10, into the form of an inverted V. The lower portions

of the V are bent again as at 11 to form vertical portions 12, 12. The inclined portions or sign areas of the blank are indicated at 13 and 14 respectively.

The name of the street is delineated suitably on each sign area 13 and 14 respectively, so that the resultant sign or marker may be read from either side.

Contiguous with the straight or vertical 65 portions 12, 12 I provide for each portion a strap iron or the like, 15, which is riveted to the sign as at 16. Such irons project at each end beyond the sign as at 17 and 18 respectively and are then bowed in semicircular 70 outline as at 19. The bowed portions terminate in parallel ends 20 each provided with a bolt hole 21 through which a bolt 21^a is passed.

The inverted V shape of the sign together 75 with the vertical portions thereof provide considerable strength and rigidity; light metal being generally employed for such signs in order that the letters 22 may be embossed thereon if desired. The strength so 80 provided is further increased by reason of the re-enforcements provided by the strap irons.

The inverted V shape, in addition to providing strength provides for a sign area at 85 each side and, what is more important, overhead illumination shines down on the sign areas and illuminates them so that they are discernible in daylight or at night for considerable distances. The inverted V shape 90 also provides for illuminating both sides by a single source of light; as will appear more particularly hereinafter.

The numeral 23 indicates one form of ornamental lighting fixture or post common 95 to municipalities and embodies two arms 24 each holding an upright lamp 25.

The sign is held between and below the lamps as shown in Fig. 4, by means of the respective strap irons being arranged to embrace respective arms 24. Tightening of the bolts 21 provides for securely anchoring the sign at each end of the lighting fixture.

In Fig. 5 I have shown the preferred arrangement for the fixtures shown in Fig. 4. 105 The intersection represented in Fig. 5 is formed by two avenues of travel, 27 and 28 respectively. Two fixtures of the type shown in Fig. 3 are ample for the intersection and are placed diagonally opposite, one 110 on one corner and the other on a diagonally opposed corner. The sign on fixture 27^a

2
indicates the name of the street which the sign thereof parallels. The fixture 28^a is arranged to parallel the avenue 28 and indicates such avenue. The fixture 27^a can be read easily by anyone approaching same on avenue 28 while the fixture 28^a is likewise visible to those travelling avenue 27. Of course, both are visible as well, but at closer range, by those travelling the same avenue 10 which the sign parallels. In the case of fixtures of the type shown in Fig. 4, both lamps assist in lighting the sign areas while providing the improved street illumination and the ornamental appearance common to double 15 lights of this type.

In Fig. 6 two signs are shown held by only two strap irons 15^a and 15^b respectively. Iron 15^a is bent at a right angle as at 30, while the other iron is semicircularly disposed as at 31 and is divided as at 32. The divided portions are held by a bolt as at 33. This form of sign readily embraces a post 34 so that one sign is at right angle to the other. Each sign is of the inverted V shape 20 and has two sign areas similar to the sign shown in Fig. 1. This sign may be placed at a corner as shown in Fig. 7 and only one such sign is needed at an intersection. A single lamp 35 is placed immediately above this 25 double sign so as to illuminate all four sign areas equally and efficiently.

Either of the signs described may be applied to a post such as 36. Such posts are usually found at intersections having an arc 30 light (not shown) centrally of the street and energized by wires (not shown) which are supported by a pair of posts of the type shown in Fig. 8. An overhanging lamp 37 of small power may be placed over the sign 35 shown and may be energized by the wires which the pole supports. While the sign shown in Fig. 1, or the sign shown in Fig. 6, may be applied to the post 36, the embodiment which is actually shown applied to the 40 post in Fig. 8, differs slightly in design. This sign is constructed so that the strap irons continue from one end only inasmuch as the sign is to be held at one point only.

Obviously, numerous other arrangements 45 of my improved sign, either in single or multiple form, will suggest themselves to the

50 minds of those skilled in the arts and I do not limit myself to the specific constructions and arrangements shown and may alter or variously arrange the signs as I desire, or 55 as occasion requires, without enlarging the scope of my invention, within the appended claims.

An example of another form of construction is shown in Fig. 9. In this form, the lighting fixture 23 is monolithic or of other suitable integral construction. The sign 1, which is of triangular or inverted V section, is cast or formed integrally with the arms 24. The wording thereon may be delineated 60 in any suitable manner, as by being painted thereon or cast in relief.

I claim:

1. In a street marker a plate bent along its longitudinal median line into inverted V section to provide parallel upwardly converging sign areas; and similar indicia on each sign area whereby the sign may be read from either side and may be illuminated from above; the lower portions of each sign area 70 being again bent to form vertically disposed portions running longitudinally of the sign; strap irons, one for, and contiguous to, each vertical portion; said irons each having corresponding ends projecting beyond the sign 75 and arranged to embrace a post.

2. The sign as in claim 7 and further including a light above said sign having its median line on a plane with the median line toward which the sign areas converge.

3. The sign as in claim 7 and further including a pair of lights; one at each end of the sign plate and each light having its median line on a plane with the median line toward which the sign areas converge.

4. Street marking and illuminating means comprising in combination a post, a pair of spaced branching arms to said post; each provided with a light, a sign member horizontally disposed between and connecting said arms; said sign member disposed below said lights and presenting a pair of opposed upwardly converging surfaces meeting at an apex below said lights, and similar indicia on each such surface.

JOHN W. DE FORD.
